United States Patent Office

Des. 196,369
Patented Sept. 24, 1963

196,369

PLAQUE OR SIMILAR ARTICLE

John M. Lee, 105 N. Fairfield, Ligonier, Pa.

Filed July 27, 1959, Ser. No. 56,944

Term of patent 14 years

(Cl. D29—23)

The FIGURE is a plan view of a plaque or similar article showing my new design.

The design is of conventional thickness.

I claim:

The ornamental design for a plaque or similar article, as shown and described.
